UNITED STATES PATENT OFFICE.

JOSEPH A. BUSCH, OF TOLEDO, OHIO, ASSIGNOR OF SIXTY PER CENT. TO ARNOLD A. POOL, OF TOLEDO, OHIO.

DESIGN FOR THE HEAD OF A CLOTHES-STICK.

57,112.

Specification for Design.

Patented Feb. 22, 1921.

Application filed February 6, 1920. Serial No. 356,741. Term of patent 14 years.

To all whom it may concern:

Be it known that I, JOSEPH A. BUSCH, a citizen of the United States, residing at Toledo, in the county of Lucas and State of Ohio, have invented a new, original, and ornamental Design for the Head of a Clothes-Stick, of which the following is a specification, reference being had therein to the accompanying drawings.

Fig. 2 is an end view in side elevation of the head.

Fig. 3 is a top plan view of the head.

Fig. 4 is a bottom plan view of the head.
I claim:

The ornamental design for the head of a clothes stick, as shown.

In testimony whereof I hereunto affix my signature.

JOSEPH A. BUSCH.
